(57) **CLAIM**

The ornamental design for an extruded channel locking joint member for joining and securing sheet material to a framework, as shown and described.

DESCRIPTION

FIG. 1 is a front, top and right side perspective view of an extruded channel locking joint member for joining and securing sheet material to a framework, showing our new design; FIG. 2 is a back, bottom and left side perspective view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.
